US0D1047090S

(12) **United States Design Patent** (10) Patent No.: **US D1,047,090 S**
(45) Date of Patent: ** Oct. 15, 2024

(54) **FOLDABLE BATHTUB**

(71) Applicant: **Huizhou Chuandong Technology Automation Co., Ltd.**, Huizhou (CN)

(72) Inventor: **Shuqun Yuan**, Guangdong (CN)

(**) Term: **15 Years**

(21) Appl. No.: **35/521,283**

(22) Filed: **May 11, 2024**

(80) **Hague Agreement Data**

Int. Filing Date: **May 11, 2024**

Int. Reg. No.: **DM/237544**

Int. Reg. Date: **May 11, 2024**

Int. Reg. Pub. Date: **Jun. 14, 2024**

(30) **Foreign Application Priority Data**

Nov. 29, 2023 (CN) 202330784135.1
